UNITED STATES PATENT OFFICE

WILLIAM H. KELLY, OF PITTSBURG, KANSAS

HAIR CLIPPER

Application filed March 29, 1927. Serial No. 179,324.

This invention relates to new and useful improvements in hair clippers.

The primary object of my invention is to provide a hair clipper in which the jaws of the upper and lower plates are made concave or curved upwardly and the teeth gradually beveled or tapered to a point.

With the hair clippers now in use, a shoulder is left which must be eliminated with the use of shears and a comb and it is the principal object of my invention to provide a hair clipper which will graduate the cut and eliminate this unnecessary additional time and labor.

15 In the accompanying drawings, which are for illustrative purposes only and are therefore not drawn to scale:

Figure 1 is a plan view, illustrating the application of my invention.

20 Figure 2 is an edge view.

Figure 3 is a vertical transverse section of the cutters, taken on line 3—3 of Figure 1.

Figure 4 is a plan view of the lower stationary plate of the hair clippers and Figure 25 5 is a similar view of the upper plate.

Referring to the drawings for a more particular description of my invention and in which drawings like parts are designated by like reference characters throughout the several views, A designates the lower stationary plate of the hair clipper, B the upper plate which is mounted to reciprocate back and forth on the lower plate and C the operating handles for the upper plate.

35 In carrying out my invention, the jaw 1 of the upper plate B is made slightly concave or curved upwardly and the cutting teeth 2 of the jaw gradually beveled or tapered outwardly to a point while the jaw 3 of the lower plate has its upper surface 3' curved to conform with the curvature of the bottom face of the jaw 1 and is also provided with cutting teeth 4 which are beveled or tapered outwardly and curved upwardly and co-act with the teeth 2 in the cutting operation. In forming the jaw 1 of the upper plate in the manner shown, a straight shoulder 5 is formed at the back of the jaw 1 which works against a corresponding shoulder 6 formed at the back of the jaw of the lower plate.

The upper face of the lower stationary plate is formed just behind the shoulder 6 with a transverse groove or recess 7 which extends across the full width thereof and with a second corresponding groove or recess 8 which also extends across the entire width of said plate behind and in parallel relation with the groove or recess 7. The aforesaid grooves or recesses 7 and 8 prevent binding of the upper plate and the lower stationary plate in the operation of the device.

55 The construction of the clippers is otherwise the same as now employed and the principal object of my invention is to so form or construct the cutting teeth that the time and labor now required in eliminating the usual shoulder left after the use of the clippers and by employing shears and a comb, may be saved.

60 From the foregoing description, taken in connection with the drawings, it is thought that the construction, operation and advantages of my invention will be readily understood without requiring a more extended explanation.

65 70 Having described my invention, what I claim as new and desire to secure by Letters Patent, is:

A hair clipper comprising a flat upper movable plate formed with an upwardly curved or concave offset jaw whose teeth are tapered or beveled outwardly to a point and a flat stationary lower plate having an offset jaw whose upper surface is curved to conform to the bottom face of the jaw of the upper plate 80 and formed with outwardly beveled teeth co-acting with those of the latter and straight co-operating shoulders formed at the back of the jaws of the upper and lower plates, the upper movable plate mounted to reciprocate 85 back and forth on the lower plate and the lower plate provided in its upper face with transverse parallel grooves which extend entirely across the width thereof and prevent binding of the upper plate in the operation 90 of the device.

95 In testimony whereof he affixes his signature.

WILLIAM H. KELLY.
